UNITED STATES PATENT OFFICE.

AUGUSTUS ABBOTT, OF DENVER, COLORADO.

COIN-CONTROLLED VENDING-MACHINE.

1,273,116.

Specification of Letter's Patent.

Patented July 23, 1918.

Application filed May 31, 1917. Serial No. 172,011.

To all whom it may concern:

Be it known that I, AUGUSTUS ABBOTT, a citizen of the United States, residing at Denver, in the county of Denver and State 5 of Colorado, have invented certain new and useful Improvements in Coin-Controlled Vending-Machines, of which the following is a specification.

My invention relates to coin-controlled 10 vending machines and its primary object resides in providing a mechanism of very simple construction the operation of which is controlled by the dropping of a coin of predetermined value, to deliver one of a 15 quantity of articles contained in a receptacle to which the mechanism is applied.

My vending machine is particularly adapted for the delivery of cigars from a box placed in the receptacle and it comprises 20 with this end in view, in combination with a receptacle of suitable proportions, a normally inoperative lifting device which when released by the dropping of a coin through a slot of the machine, may be operated to 25 withdraw a single cigar from a quantity contained therein and transfer the same to a receiver which delivers it outside the receptacle.

An embodiment of my improved coin-controlled mechanism has been illustrated in 30 the accompanying drawings in the several views of which like parts are similarly designated and in which—

Figure 1 is a perspective view of my vending machine in its preferred form,

Fig. 2, an enlarged section in a vertical plane indicated by the line 2—2, Fig. 1,

Fig. 3, a horizontal section taken along the line 3—3, Fig. 1,

Fig. 4, a longitudinal section through the sheath in which the lifting device of the machine has its movement,

Fig. 5, a sectional view of a lifting device of modified construction and

Fig. 6, a perspective view showing another modification of said device.

Referring to the drawings by numerical reference characters, 2 designates a case covered by a flanged lid 3 which is hinged as 50 at 4 and which is secured in its closed position by means of a padlock 5.

The lid and the front of the case have glass-covered openings 6 and 7 to permit of the inspection of the contents of the case from without the same. The lid of the case has a coin-slot 8 at the lower end of a pocket

9 which is formed upon the face of one of two upright flanges 10 which conjointly provide a guide which directs the operative movement of the lifting device, and its position when at rest, as will hereinafter be more fully explained.

Disposed beneath the coin-slot 8 is a narrow inclined chute 12 through which the coin moves to release the normally inoperative lifting device and which communicates with an inclined trough 13 in which the coins are collected after the lifter has been released through the instrumentality thereof.

The lifter hereinbefore repeatedly referred to comprises in its preferred form, a spear-like instrument composed of a shank or shaft 14 secured at one of its ends in a handle 15 and provided at its opposite end with a pair of sharp-pointed needles 16.

The shank of the spear is longitudinally slidably fitted in a sheath 17 which extends through an opening in the lid of the case and it is mounted in bearings 18 for pivotal movement about a transverse axis adjacent said opening.

A stop 43 on the shank of the lifting device limits its outward movement by engagement with the inner end of the sheath and cooperates with the shoulder 44 formed at the junction of the shank with the handle 15 to direct the movement of the lifter and thereby prevent a cigar impaled upon the needles at its ends from coming in contact with any part of the case and the mechanism inclosed therein.

The opening through which the lifter extends is closed by a cylindrical boss 19 formed integral with the sheath 17 and provided with trunnions 20 for its pivotal support in the bearings which are secured to the lid 3.

A flat-spring 21 secured at one of its ends to the portion of the sheath within the case, bears upon the shank of the lifting device to 100 frictionally hold it in its adjusted positions with relation to the sheath.

The means for detaching the article to be delivered from the needles at the end of the shank, consists in the construction shown in 105 the drawings of a push-arm 22 which is pivoted to the lid of the casing at a point 23 forward of the pivotal axes of the lifter and which has a bifurcated end 24 which straddles the shank of the same.

It will be seen that during upward movement of the lifter about its pivotal axis, the

forked end of the releasing device moving through a different arc, slides along the shank thereof and by engagement with an article impaled on the needle, pushes it free 5 therefrom.

The article thus released, falls into a chute 25 which extends through a port 26 in the face of the casing.

The coin-chute 12 has in the upper edges 10 of its parallel sides, two sets of notches 26 and 27, one of which prevents the operation of the lifting device without the deposit of a coin of the determinate size in the pocket 9, while the other limits the pivotal movement 15 of the lifter after it has been released through the instrumentality of the coin.

With these ends in view, the lifting device is provided with a stop 28 which is pivoted on its sheath as at 29 and which is held in 20 constant engagement with the edges of the chute by a spring 30.

The depth of the forward set of notches is such that a coin 31 held in the chute by engagement with the end of the stop, bridges 25 the gap thereof and thereby permits of the movement of the stop across the notch for the pivotal movement of the lifter to a position in which its point can engage any one of a quantity of articles in the lower portion 30 of the case.

In Figs. 1 and 2 of the drawings, the reference numeral 32 designates a cigar-box which is placed upon the bottom of the case with its lid 33 held in the open position by 35 means of a brace 34.

The box contains a quantity of cigars designated by the numeral 35 and it is the purpose of the mechanism to remove the cigars singly from the box after a coin has been deposited 40 in the pocket 9, and transfer the same to the receiver 25 which discharges outside the case.

To produce this result, a coin of the required value is deposited in the pocket and 45 rolls downwardly through the chute until its movement is arrested by engagement with the stop 28 on the sheath of the lifting device which normally rests upon a seat 42 formed on the two flanges 10, with the end 50 of its handle 15 in engagement with the edges of the same which are of arcuate form for the guidance of the device during the operative movement.

The coin in this position bridges the forward 55 set of notches in the edges of the chute, which otherwise arrest the pivotal movement of the device by engaging the end of its spring-pushed stop.

The stop being through the instrumentality 60 of the coin enabled to move across the notches 36, permits of the pivotal movement of the lifting device to bring the needles at the end of its shank in contact with any one of the cigars contained in the box.

65 The operator after selecting a cigar from

the quantity clearly visible through the glass-covered openings of the lid and the front of the case, turns the lifter about its pivot until its lower end is above the selected article and then presses it downwardly 70 through the sheath until the needles have penetrated the cigar.

The operator now lifts the cigar impaled on the needles, out of the box by outward movement of the shank 14 until the stop 36 75 engages the end of the shank. The lifting device is subsequently moved about its pivot in which movement it is guided by the engagement of the shoulder 44 of its handle 15, with the arcuate edges of the flanges 10. 80 At the termination of this movement the cigar is pushed off the needles by the action of the releasing means hereinbefore described, and the lifting device is again in its position of rest upon the seat 42. 85

The released cigar falls in the receiver 25 and is delivered outside the case to be removed by the purchaser.

It will be understood that any attempt made to operate the machine by a coin smaller than that of the predetermined value, is frustrated by its movement through the chute 12 without engaging the end of the stop 28, and that the size of the pocket 90 into which the coins are deposited forbids the use of a larger coin. 95

The deposited coins which are collected in the trough 13 are clearly visible through the glass-covered openings of the lid and the front of the case so that any attempt to operate the machine by the use of any other article than a coin of the required value is 100 readily detected.

The two needles at the end of the shank prevent displacement of the cigar with relation thereto during its upward movement, it being understood that it is essential for the proper operation of the machine that the cigar be constantly held in a substantially horizontal position. 105

In Fig. 5 is shown a substitute for the needles which consists of a flat spring 36 which is bent so that its end portions diverge from a point of contact 37 to grasp a cigar or similar object. 110

A spreader which separates the end-portions of the spring to permit of their embracing the cigar, consists of a rod 38 which extends through the hollow shank of the lifting device and which has at its lower end a conical point 39 to engage the spring portions adjacent their point of contact and at its opposite end a knob 40 which may be depressed at the outer end of the shank. 120

In the form shown in Fig. 6 of the drawings the holding device of the lifter consists of two resilient blades 41 which are fastened at the end of the shank so as to readily separate by contact with the article 125 to be transferred. 130

Other modifications in the construction and arrangement of the parts of my improved mechanism may be made within the scope of my invention as set forth in the following claims.

I claim—

1. A coin-controlled vending-machine comprising a receptacle having a slot for the deposit of coins, and a port for the delivery of purchased articles, a receiver in connection with said port, a pivoted and longitudinally movable lifting-device extending through an opening in the receptacle, to reach any one of a quantity of articles contained therein, said device including a holding-member adapted to secure one of said articles during its lifting action, a chute connected with the coin-slot of the receptacle and having in its upper edge, a notch adapted to be bridged by a coin of determinate size, a stop on the lifting device bearing upon said edge of the chute to engage said notch and thereby prevent the pivotal movement of the lifting device, the stop being normally disposed to engage the edge of a coin which bridges the notch, and the chute having in its edge a second notch to limit the pivotal movement of the lifting device by engagement with the stop after it has passed across the first-mentioned notch, and means for detaching an article from the holding-member of the lifting device by its movement to a point above said receiver.
2. A coin-controlled vending-machine comprising a receptacle having a slot for the deposit of coins, and a port for the delivery of purchased articles, a receiver in connection with said port, a pivoted and longitudinally movable lifting device extending through an opening in the receptacle, to reach any one of a quantity of articles contained therein, said device including a holding-member adapted to secure one of said articles during its lifting action, a chute connected with the coin-slot of the receptacle and having in its upper edge, a notch adapted to be bridged by a coin of determinate size, a spring-pressed stop on the lifting-device bearing upon said edge of the chute to engage said notch and thereby prevent the pivotal movement of the lifting device, the stop being normally disposed to engage the edge of a coin which bridges the notch, and means for detaching an article from the holding-member of the lifting device by its movement to a point above said receiver.
3. A coin-controlled vending-machine comprising a receptacle having a slot for the deposit of coins, and a port for the delivery of purchased articles, a receiver in connection with said port, a lifting device adapted to reach any one of a quantity of articles contained in the receptacle and com-
- posed of a pivoted sheath extending through an opening of the receptacle, a shank longitudinally movable in said sheath, and a holding member at the inner end of the shank, to secure one of said articles during its lifting action, a locking mechanism normally preventing the pivotal movement of said device and adapted to release the same through the instrumentality of a coin of determinate size, deposited in the slot of the receptacle, and means for detaching an article from the holding-member of the lifting-device by its movement to a point above said receiver.
4. A coin-controlled vending-machine comprising a receptacle having a slot for the deposit of coins, and a port for the delivery of purchased articles, a receiver in connection with said port, a lifting device adapted to reach any one of a quantity of articles contained in the receptacle and composed of a pivoted sheath extending through an opening of the receptacle, a shank longitudinally movable in said sheath, a spring to maintain the shank in its adjusted positions relative to the sheath, and a holding member at the inner end of the shank, to secure one of said articles during its lifting action, a locking-mechanism normally preventing the pivotal movement of said device and adapted to release the same through the instrumentality of a coin of determinate size, deposited in the slot of the receptacle, and means for detaching an article from the holding-member of the lifting-device by its movement to a point above said receiver.
5. A coin-controlled vending-machine comprising a receptacle having a slot for the deposit of coins, and a port for the delivery of purchased articles, a receiver in connection with said port, a lifting device adapted to reach any one of a quantity of articles contained in the receptacle and composed of a pivotal sheath extending through an opening of the receptacle, a shank longitudinally movable in said sheath, a circular boss on the sheath closing the opening of the receptacle through which it extends, and a holding member at the inner end of the shank, to secure one of said articles during its lifting action, a locking mechanism normally preventing the pivotal movement of said device and adapted to release the same through the instrumentality of a coin of determinate size, deposited in the slot of the receptacle, and means for detaching an article from the holding-member of the lifting-device by its movement to a point above said receiver.
6. A coin-controlled vending-machine comprising a receptacle having a slot for the deposit of coins, and a port for the delivery of purchased articles, a receiver in connection with said port, a pivoted and longitudinally movable lifting-device ex-

tending through an opening in the receptacle, to reach any one of a quantity of articles contained therein, said device including a holding-member adapted to secure one 5 of said articles during its lifting action, a locking mechanism normally preventing the pivotal movement of said device and adapted to release the same through the instrumentality of a coin of determinate size, deposited 10 in the slot of the receptacle, and means for detaching an article from the holding-member of the lifting-device by its movement to a point above said receiver, consisting of a pivoted push-arm having a 15 fork riding along the lifting device during the pivotal movement thereof.

7. A coin-controlled vending machine, comprising a receptacle having a slot for the deposit of coins and a port for the delivery 20 of purchased articles, a receiver in connection with said port, a pivoted and longitudinally movable lifting device extending through an opening of the receptacle and adapted to reach any one of a quantity of 25 articles contained therein, a locking mechanism normally preventing the pivotal movement of said device and adapted to release the same through the instrumentality of a coin of determinate size deposited in the 30 slot of the receptacle, a guide on the receptacle directing the pivotal movement of the lifting device by limiting the inward longitudinal movement thereof, means for limiting the outward longitudinal movement of 35 the device, and means for detaching an article from the lifting-device by its movement to a point above said receiver.

8. A coin-controlled vending machine comprising a receptacle having a slot for the 40 deposit of coins and a port for the delivery of purchased articles, a receiver in connec-

tion with said port, an arcuate guide-flange on the receptacle, a lifting device adapted to reach any one of a quantity of articles contained in the receptacle and composed of a 45 pivoted sheath extending through an opening of the receptacle, a shank longitudinally movable in said sheath, and a holding-member at the inner end of the shank, said shank having a stop to limit its outward longitudinal movement by engagement with the sheath, and a shoulder to limit its inward longitudinal movement by engagement with said guide-flange, a locking-mechanism normally preventing the pivotal movement of 50 said device and adapted to release the same through the instrumentality of a coin of determinate size, deposited in the slot of the receptacle, and means for detaching an article from the holding-member of the lifting device by its movement to a point above 55 said receiver.

9. In a coin-controlled vending-machine, a receptacle having a coin-slot and a delivery port, a coin-controlled lifting-device including an arm extending through an opening in the top of the receptacle and mounted to swing in a vertical plane about a transverse axis and to move longitudinally in a direction transverse to said axis, whereby to 60 reach any one of a quantity of articles contained in the receptacle, and means for detaching an article lifted by said device by its movement to a determinate point of discharge. 75

In testimony whereof I have affixed my signature in presence of two witnesses.

AUGUSTUS ABBOTT.
